UNITED STATES PATENT OFFICE

112,864

DESIGN FOR A COMBINED SEAT AND CABINET

Emil J. Schlup, Terre Haute, Ind.

Application February 12, 1938, Serial No. 75,107

Term of patent 7 years

To all whom it may concern:

Be it known that I, Emil J. Schlup, a citizen of the United States and a resident of Terre Haute, county of Vigo, and State of Indiana, have invented a new, original, and ornamental Design for a Combined Seat and Cabinet, of which the following is a specification, reference being had to the accompanying drawing, forming part thereof.

In the drawing, Fig. 1 is a front perspective view of the combined seat and cabinet embodying the design, the door being illustrated in partially opened position.

Fig. 2 is a rear perspective view; and
Fig. 3 is a top plan view thereof.

I claim:

The ornamental design for a combined seat and cabinet as shown.

EMIL J. SCHLUP.
